UNITED STATES PATENT OFFICE.

WILLIAM JAMES ASHTON, OF DALLAS, TEXAS.

MOTOMETER-ANCHOR.

1,390,975.

Specification of Letters Patent. Patented Sept. 20, 1921.

Application filed January 10, 1921. Serial No. 436,261.

To all whom it may concern:

Be it known that I, WILLIAM JAMES ASHTON, a citizen of the United States, residing at Dallas, in the county of Dallas and State 5 of Texas, have invented a new and useful Motometer-Anchor, of which the following is a specification.

The object of my invention is to provide a means whereby a motometer can be anchored 10 securely to the radiator of an automobile, thus making theft of same impossible, or so difficult that it will not be attempted.

The nature of my invention will be fully understood from the following description 15 taken in connection with the accompanying drawings, forming part hereof, in which—

Figure 1 is a vertical section showing a radiator filling cap and motometer in place, with my improved anchor attached; Fig. 2, 20 is an elevation view of the anchor and parts ready to be attached to the motometer; Fig. 3, is a section showing cap removed and motometer tilted to one side to give space for filling the radiator with water; Fig. 4, 25 is a detail section of link and anchor taken on line 4-4, of Fig. 2; Fig. 5, is a perspective view of a simple, modified form of my invention.

Similar numerals refer to similar parts 30 throughout the several views.

Referring now to the drawings in which the numeral 1 is an ordinary type of motometer attached to a radiator filling cap by means of the nut 3 having a protecting cap 35 4 screwed to its lower extremity. In the end of cap 4, is swiveled the eye 5, to which is attached the link 6. Depending from the link 6, is an anchor bar 7. It can be seen that the anchor 7, is limited in rotation be- 40 cause of contact with the vertical overflow pipe 8, therefore, the swiveled eye 5, is introduced to provide proper means of rotation of the cap 2, in order that it may be un- 45 screwed and removed for filling the radiator with water.

The anchor consists of a metal bar 7, from which projects a centrally located right angle arm 9, with a slot 10, the lower end of which terminates in a circular opening 11. 50 Now by referring to Fig. 2, and Fig. 4, the object of this slot and opening will be made clear. The link 6, is moved downward in the slot to the circular opening 11, thus permitting the anchor 7, to be tilted to an ap- 55 proximate parallel position with the link 6 as shown by a dotted line position 12. In

this position it can be lowered into the radiator through the filling spout, where, when it is free to do so, the anchor resumes its normal horizontal position by gravity; the 60 link 6, following the slot 10, to its uppermost end. It will be noted that the link 6, and arm 9, are of rectangular construction, thereby locking one into the other, when the link 6, is at the top terminus of the slot 10. 65 This locking of the two members, as described, prevents the anchor from being raised, while in the radiator, to a parallel position to the link, with a wire or other like instrument, in the hands of an unscrupulous 70 person, who might attempt to withdraw same through the radiator filling spout.

After the anchor has been placed in the radiator the cap 4, is screwed to the lower end of the motometer and securely attached to 75 same by the set-screw 13. The head of the set-screw is then removed with a file, thus preventing anyone, by ordinary means, from removing same, and unscrewing motometer from the cap 4. Any attempt to remove the 80 motometer from the car, to which it is thus attached, will be prevented by the anchor, which will catch and hang to the side of the radiator 14. Fig. 5, shows a modified form 85 of my invention in which the link 6', is made of round material and linked to the anchor 7', through the hole 11'. It is obvious that in this form the anchor bar must be more than twice the length of the radiator opening that both ends might at all times engage 90 the sides of said opening to prevent its withdrawal through same. While this form embodies the spirit and principle of my invention, it could not, on account of the length, be inserted in radiator where the distance between the top of the radiator and 95 the cooling cells is limited.

Having thus described the nature and object of my invention, what I claim as new and desire to secure by Letters Patent of 100 the United States is—

1. A motometer anchor, consisting of a metal bar, with a centrally located right angle arm; in said arm a slot terminating in a circular aperture at its lower extremity.
2. A motometer anchor having a slot, in combination with a link with rectangular sides to engage in said slot and prevent said anchor from turning on said link, substantially as described.
